UNITED STATES PATENT OFFICE.

THOMAS RUSHTON, OF TOLLINGTON PARK, LONDON, ENGLAND, ASSIGNOR TO COVENTRY
ELECTRIC CLOCK COMPANY LIMITED, OF LONDON, ENGLAND.

ELECTRIC CLOCK.

1,275,606.

Specification of Letters Patent. Patented Aug. 13, 1918.

Application filed April 18, 1914. Serial No. 832,966.

To all whom it may concern:

Be it known that I, THOMAS RUSHTON, a subject of the King of Great Britain, residing at 51 Birnam road, Tollington Park, in the county of London, England, have invented new and useful Improvements in Electric Clocks, of which the following is a specification.

This invention relates to electric clocks which are wound at intervals by an electromagnetic the circuit of which is automatically closed by the clock.

The invention comprises an electromagnetic driving and contact mechanism including a longitudinally movable worm subjected to end pressure, adapted to rotate the clock train and itself to be rotated by electromagnetic means, and controlling by its longitudinal movement the electric circuit of the apparatus.

The invention further includes an improved electrical contact for such electromagnetic driving mechanism, one portion of which is constituted by a rotatable arbor which revolves while making contact with a non-rotary member.

The invention consists also in a clock maintained in motion by endwise pressure on a worm engaging the clock train, the said worm being traversed longitudinally at intervals against such endwise pressure as the result of rotation effected by electromagnetic means the circuit of which is controlled by the longitudinal movement of the worm.

Constructions according to the invention are illustrated in the accompanying drawings in which—

Figure 1 shows the electromagnetic winding and contact apparatus assumed to be winding the ordinary driving spring (not shown) of a clock train.

Figs. 2 and 3 are details of alternative constructions.

Figs. 4, 5 and 6 are side and end elevations respectively of an electromagnetically driven clock which has no driving spring other than that bearing on the worm shaft.

Fig. 7 is a detail of a contact mechanism of this clock.

In the arrangement of Fig. 1 a spur wheel

1 on the spring drum (not shown) is rotated for winding purposes by means of a pinion 2 on the shaft 3. This latter carries a worm wheel 4 meshing with the worm 5, the shaft 6 of which bears a ratchet wheel 7 adapted to be rotated by the electromagnetic winding device. The shaft 6 is movable longitudinally in bearings. The tension of the driving spring action through the gearing 1, 2, 3, 4, 5 tends to move it in one direction, and a leaf or other spring 8 bearing on one end of it counteracts this pressure. The opposite end of the shaft 6 is cut into facets 9 so as to present grinding edges and bears against a silver or like facing 10 upon an adjustable terminal block 11 which is mounted on but insulated from the frame of the clock. This block is joined by a conductor 12 to one pole of a suitable battery 30 or other source of supply.

The electromagnetic winding device by which the spring 8 is restored to its initial position, after it has caused the closing of the circuit may be of the form shown in Fig. 1. This comprises an electromagnet 13 the armature 14 of which carries a hammer 15 to regulate its rate of vibration. It also bears a contact spring 16, which, when the armature is not attracted, rests against a contact screw 17 which is joined by a conductor 18 to one terminal of the magnet winding, the remaining terminal being connected by the lead 19 to the other pole of the battery or other source of power. The terminal screw 17 is insulated from the clock frame. Thus the complete circuit of the electromagnetic device is as follows: from the battery by lead 12, through terminal 11, contact 10, shaft 6 of the worm, the frame of the clock, the armature 14, the spring 16, the contact 17, lead 18, the windings of the electromagnet, and lead 19 to the battery. When the armature is attracted, contact is broken between 16 and 17, with the result that the armature is at once released and moves back to the position shown under the action of spring 20. Pivoted upon the armature 14 is a spring-pressed pawl 21 which engages the ratchet teeth 7. Thus as the armature oscillates it rotates the shaft 6. If desired the armature may carry two pawls,

one of which operates when the armature is attracted and the other when it recedes from the magnet, so that the shaft 6 is rotated one step for each stroke of the armature, *i. e.*, 5 two steps for each complete oscillation.

When the driving spring is sufficiently wound its pressure upon the worm shaft 6 through the gearing 1, 2, 3, 4, 5 moves the shaft longitudinally against the action of 10 spring 8 so as to separate the end 9 from the contact 10. As the tension in the driving spring lessens the spring 8 is able to press down the shaft 6 thus virtually winding the clock a very little without rotation of 15 the worm. The result of this is finally to bring about contact between 9 and 10, thus closing the circuit above described. The armature 14 then vibrates, rotating the shaft 6 as it recedes from its attracted position 20 and through the gearing winding the driving spring. This continues until the tension of the spring is sufficiently increased to cause the worm shaft 6 to be moved again against the action of spring 8 to break contact. 25

It is not necessary that the operating contact should be actually made by the shaft 6. An alternative construction is illustrated diagrammatically in Fig. 2. There, 22 represents a snail cam upon the shaft 6, the circumference of which is approximately circular throughout the greater part of its circumference. This forms one of the contact members. The other is a spring or spring- 30 pressed arm 23 notched at 24. Normally this arm rests upon the edge of a spring 25 which corresponds with the spring 8 bearing upon the end of the shaft 6.

When the shaft yields owing to the lessening of tension of the driving spring, the 40 movement of spring 25 brings it opposite the notch 24, with the result that the arm 23 falls. It thus makes contact with the cam 22 completing the winding circuit. In 45 winding, the cam 22 is rotated and lifts the arm 23 to such a position that the spring 25 can reengage with it. Such reengagement will take place when the driving spring is sufficiently tensioned to overcome the spring 50 25. After this has occurred the further rotation of the cam 22 will break the circuit because the arm 23 will not fall when it comes to the step of the cam.

Yet another arrangement of the contacts 55 is shown diagrammatically in Fig. 3 where 26 represents a snail cam upon the shaft 3 or other shaft driven therefrom. Upon this cam rests the insulating end 27 of a contact spring 28. A second contact spring 29 is pressed against the spring 28 except in the 60 position shown in the drawing. In this position the end of the spring 29 is upheld by the step of the cam for a short interval after the spring 28 has fallen.

When the spring 8 is able to overcome the 65 driving spring the longitudinal motion of the worm 5 will cause the cam 26 to rotate slightly just sufficient to release the spring 29. The two springs thus come in contact and the winding circuit is closed. They 70 continue in contact until the cam has made one revolution, when the fall of spring 28, which is prior to the release of spring 29, breaks the circuit.

It will be apparent from the above description that the worm effects some portion of the winding of the main spring by its longitudinal motion under the action of spring 8. Where there is a driving spring of the ordinary form this portion of the 80 winding is small compared with that which is effected by the rotation of the worm. But if a stiff driving spring is employed a comparatively small amount of winding of the spring will correspond with the normal 85 range of displacement of spring 8, and the longitudinal motion of the worm will account for a larger proportion of the total amount of winding. The stiffer the driving spring the less will be the rotation of pinion 90 4 during the vibration of the armature. If the ordinary driving spring be altogether omitted, that is the same as making it infinitely stiffer. Spring 8 is then the only driving spring in the clock and the drive of 95 the clock is brought about by the longitudinal motion of the shaft 6. The rotation of the shaft by the electromagnet does not cause any substantial rotation of the wheel 4 but rather causes the worm to screw past the 100 wheel and displace the spring 8. The construction of Figs. 4-7 is designed to work in this fashion.

In the arrangement of these figures, the operating electromagnet is indicated at 31. Its armature 32 is pivoted at 105 33 and is normally pressed into unattracted position by the spring 34 the tension of which may be adjusted by a screw 35. The prolongation of spring 34 forms also the back contact 36 of the armature, which, 110 when the armature is unattracted, rests against adjustable screw 37. At its free end the armature carries a leaf spring 38 forming a pawl which engages with a fine milled ratchet wheel 39 secured on a worm shaft 115 40 carrying at 41 a worm which engages the first wheel 42 of the clock train. The worm wheel 42 has a wheel 50 on its arbor meshing with a pinion 51 on the same arbor as a wheel 52, which in its turn drives the 120 pinion 53. The last wheel 43 of the clock train is a crown wheel on the arbor of pinion 53 and engaging the pinion 54 of an escape- 125 ment mechanism, indicated at 46, which controls the motion of the train.

The spindle 40 is longitudinally movable and is normally pressed to the right in Fig. 4 by a leaf spring 44. Its right hand end

forms a contact—it preferably being somewhat pointed and formed with facets which can abut upon the fixed contact 45.

The method of operation of this apparatus is closely analogous to that of the clock first above described. But now the spring 44 is the only spring of the clock. The armature 32 when attracted breaks its back contact 36, and proceeding further under its own momentum takes up a tooth of the ratchet wheel 39. In returning under the action of its spring 34 it rotates the ratchet wheel 39 and screws the worm 41 past the wheel 42, pressing back the spring 44 and also breaking contact between the shaft and the contact 45. The spring 44 drives the clock train through the worm 41 acting as a rack until contact is again made in the worm spindle and contact 45. Winding then again takes place, the armature 32 making a single vibration and breaking the contact between the worm spindle and contact 45 before it re-makes its back contact 36.

It will be apparent that the spring 44 could readily be replaced by a weight bearing directly or indirectly upon the spindle so as to press it endwise. Such a construction would be useful in connection with turret and other large and exposed clocks.

30 What I claim is:

1. In an electric clock the combination of a train of wheels, a worm engaging one member of said train and formed at one end as an electrical contact, a fixed contact serving as an abutment for the contact end of said worm, a spring pressing said worm longitudinally to close said contacts and electro-magnetic means for rotating said worm in order to wind the clock, and conducting means for electricity including a source of electricity from the contact to the electro magnetic means.

2. In an electric clock the combination of a train of wheels, a worm engaging with one member of said train, an electro-magnet for rotating said worm in step-by-step fashion, a fixed contact serving as an abutment for one end of said worm and a spring pressing upon the other end of said worm to close said contact and to drive said train, and of such dimensions as to be fully stressed by a single stroke of said electro-magnet, and conducting means for electricity including a source of electricity from the contact to the electro magnetic means.

3. In an electric clock, the combination of a train of wheels, a worm engaging one member of said train, electro-magnetic means for rotating said worm to wind the clock, an electrical contact in the circuit of said electro-magnetic means operated by longitudinal motion of said worm, and a spring pressing upon one end of said worm,

adapted both to control said electrical contact and to serve as the driving spring for 65 said train, and conducting means for electricity including a source of electricity from the contact to the electro magnetic means.

4. In an electric clock the combination of a train of wheels, a worm engaging one 70 member of said train, and formed at one end as an electrical contact, electro-magnetic means for rotating said worm in order to wind the clock, a fixed contact in the circuit of said means serving as an abutment 75 for the contact end of said worm, a spring pressing said worm longitudinally to bring said contact members into contact, in order to close the circuit of said electro-magnetic means, and a further contact in 80 said circuit in operative connection with said electro-magnetic means for opening the circuit of the latter, and conducting means for electricity including a source of electricity from the contact to the electro magnetic 85 means.

5. In an electric clock the combination of a train of wheels, a worm engaging one member of said train and formed at one end as an electrical contact, electro-magnetic 90 means for rotating said worm in order to wind the clock including a ratchet wheel in the worm, a pawl engaging the ratchet wheel, and an armature of an electro-magnet carrying the pawl, a fixed contact in the 95 circuit of said means serving as an abutment for the contact end of said worm, a spring pressing said worm longitudinally to bring said contact members into contact, in order to close the circuit of said electro-magnetic 100 means, and a further contact in said circuit in operative connection with said electro-magnetic means for opening the circuit of the latter.

6. In an electric clock the combination of 105 a train of wheels, a worm engaging with one member of said train, an electro-magnet for rotating said worm in step by step fashion, including a ratchet wheel on the worm, a pawl engaging the worm and an 110 armature of the electro-magnetic means carrying the pawl, a fixed contact serving as an abutment for one end of said worm and a spring pressing upon the other end of said worm to close said contact and to 115 drive said train, and of such dimensions as to be fully stressed by a single stroke of said electro-magnet.

In testimony whereof I have signed my name to this specification in the presence 120 of two subscribing witnesses.

THOMAS RUSHTON.
